UNITED STATES PATENT OFFICE

172,865

SMOKER'S STAND OR SIMILAR ARTICLE

Charles W. Clemens, Nashville, Tenn., assignor to Aladdin Industries, Incorporated, Nashville,
Tenn., a corporation of Illinois

Application February 12, 1954, Serial No. 28,977

Term of patent 14 years

(Cl. D85—2)

To all whom it may concern:

Be it known that I, Charles W. Clemens, a citizen of the United States, residing at Nashville, county of Davidson, and State of Tennessee, have invented a new, original, and ornamental Design for a Smoker's Stand or Similar Article, of which the following is a specification, reference being had to the accompanying drawing, forming part thereof, in which—

Figure 1 is a perspective view of a smoker's stand or similar article, showing my new design, and

I claim:

The ornamental design for a smoker's stand or similar article, substantially as shown.
